United States Patent Office.

JAMES COOK, OF WEST GROTON, MASSACHUSETTS.

Letters Patent No. 74,050, dated February 4, 1868.

TOBACCO-PIPE.

The Schedule referred to in these Letters Patent and making part of the same.

TO ALL WHOM IT MAY CONCERN:

Be it known that I, JAMES COOK, of West Groton, in the county of Middlesex, and State of Massachusetts, have invented a new and improved "Tobacco-Pipe;" and I do hereby declare that the following is a full, clear, and exact description thereof, which will enable others skilled in the art to make and use the same, reference being had to the accompanying drawings, forming part of this specification.

The present invention consists in placing, and securing so as to be detachable at pleasure, within the bowl of a pipe, a cup or receptacle for the tobacco, that, at its lower end, is provided with a series of apertures for forming a communication between it and the stem, and with a space or chamber left around and between it and the interior of the bowl, whereby the stem cannot become clogged, and the smoke, before passing to the mouth, is cooled, as well as the tobacco kept dry and free from nicotine, as it is extracted by the smoking of the pipe.

In combination with the above, a tube is inserted in the stem where it opens into the bowl of the pipe, which tube, being bent upward into the bowl, prevents the passage of the nicotine, as it is extracted from the tobacco in the inner cup or receptacle, into the stem, and thence to the mouth, the importance and advantage of which are obvious. In the accompanying plate of drawings, my improved tobacco-pipe is illustrated—

Figure 1 being a central section through the pipe, in the direction of its length, and

Figure 2 a transverse section through the bowl, taken in the plane of the line x x , fig. 1.

Similar letters of reference indicate like parts.

A, in the drawings, represents the bowl of the pipe, and B its stem, both of which may be made of any of the materials usually employed for such purposes. C, an inner cup or receptacle, inserted in bowl A, to and on the top of which it is screwed. B, a chamber or space between inner cup C and inside of tobacco-bowl A; a, apertures in sides of inner cup C at its lower end. b, a tube, inserted in stem B, where it communicates with bowl A, which tube is bent upward into the bowl.

In using the pipe constructed as above described, the tobacco is placed within the inner cup C, when, lighting it, the pipe is smoked in the ordinary manner, the smoke being drawn from the tobacco-cup through its apertures into the chamber D, and from thence through the bent tube b into the stem to the mouth.

By my improved pipe, it is obvious that the tobacco is kept dry, that the stem cannot become clogged, that the nicotine cannot pass to the mouth, that the smoke before reaching the mouth must be cool, and that the tobacco-cup can be removed for being cleaned, as well as the interior of the bowl A.

What I claim as new, and desire to secure by Letters Patent, is—

The chamber D, formed around the sides of the bowl C by suspending the latter in the screw-cap of the bowl A, as and for the purpose specified.
